(57) **CLAIM**

The ornamental design for a refill bottle, as shown and described.

DESCRIPTION

FIG. 1 is a front and side perspective view of our refill bottle; FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The features shown in broken lines in the drawings are for the purpose of illustrating environmental structure, and form no part of the claimed design.
